Primary Examiner — Melanie Pellegrini*(74) Attorney, Agent, or Firm* — Woodard Emhardt Henry Reeves & Wagner, LLP(57) **CLAIM**

The ornamental design for a shower drain, as shown and described.

DESCRIPTION

FIG. 2.1 is a side view;

FIG. 2.2 is a top view;

FIG. 2.3 is a perspective view;

FIG. 2.4 is an exploded view;

FIG. 2.5 is an exploded view; and,

FIG. 2.6 is a perspective view.

The broken lines represent environment and portions of the shower drain which form no part of the claimed design.

1 Claim, 6 Drawing Sheets(56)
